(57) **CLAIM**

The ornamental design for the “triple tier drawer for holding beverage cartridges,” as shown and described.

DESCRIPTION

FIG. 1 is a perspective view of the triple tier drawer for holding beverage cartridges;

FIG. 2 is a perspective view thereof showing the bottom drawer extended outward;

FIG. 3 is a perspective view thereof showing the bottom drawer extended outward and holding different sizes of beverage cartridges;

FIG. 4 is a front view thereof;

FIG. 5 is a rear view thereof;

FIG. 6 is a side view thereof;

FIG. 7 is a second side view thereof;

FIG. 8 is a top view thereof; and,

FIG. 9 is a bottom view thereof.

The broken lines are for illustrative purposes only and form no part of the claimed design.
